UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

RAILWAY-CAR TRUCK.

Application filed May 21, 1927. Serial No. 193,342.

This invention relates to railway car trucks.

An object of the invention is to provide a railway truck of the pedestal type in which an arrangement of equalizer bars is provided which co-operates with the journal boxes to permit the required vertical movement thereof with respect to the truck frame and with respect to each other, and wherein the equalizer bars are utilized for positively controlling the movements and positions of the journal boxes to prevent displacement thereof and consequent injury to the pedestal members.

A more particular object of the invention is to provide means of this character in which the equalizer bars are supported to swing about pivots fixed with reference to the frame, and the ends of the bars are each formed with spaced bearing portions which bear upon the top wall of the related journal box adjacent the opposite side edges thereof, so that the boxes are prevented from excessive tilting movement and are acted upon by the equalizer bars to insure proper movement of the journal boxes with reference to the pedestal members.

Other and further objects of the invention will more fully and clearly appear from the description and claims hereinafter following.

In the drawings forming a part of this specification, Figure 1 is a side elevational view of a portion of a six-wheeled truck showing my improvements in connection therewith. Figure 2 is a part sectional, part elevational view, corresponding substantially to the line 2—2 of Figure 1. And Figure 3 is a transverse sectional view of the invention corresponding substantially to line 3—3 of Figure 1.

As shown in the drawings, the frame proper of the truck is of the usual rectangular form, having longitudinally extending side beams, and transversely disposed end beams, one of said side beams being illustrated in the drawings and indicated by the numeral 10. The frame is provided with a spring suspension arrangement of a well-known type which suspends the load imposed thereon by the truck bolster or spider, only one portion of said arrangement being shown which is indicated by the numeral 11.

Pedestal members are provided three on each side of the frame in a six-wheeled truck and only two of the pedestal members are shown in the drawings, and indicated at 12

and 13, it being understood that the remaining portions of the truck not shown correspond to those illustrated. As contemplated by this invention, the pedestal 12 is made up of longitudinally extending transversely spaced walls forming jaws 14 and 15, and connecting portions 16 and 17, the portion 16 fitting on the outer side of the frame member 10, while the portion 17 is disposed upon the inner side of said frame member. The spaced walls are connected together by horizontally disposed webs 18—18 disposed on the under-surface of the frame member 10 and secured thereto by means of bolts 19, the connecting portion 16 being secured to the frame member by bolts indicated at 20 which extend through the frame member. The spaced walls are further connected adjacent the inner vertical edges of the jaws 14 and 15 by means of integral webs 21—22 which form vertically disposed journal box guide faces. The webs 21 and 22 at the lower ends are turned outwardly to provide webs 23—23 to which is secured a cross bar 24 adapted to detachably hold the journal box 25 in place.

The journal box 25 is slidably disposed between the guide faces provided by the webs 21—22, and said journal box is provided with the usual flanges 26—26 which bear upon the opposite outer faces of the pedestal member to prevent lateral displacement of the journal box. The journal box 25 includes the usual side bottom, and end walls, and a top wall, the top wall as contemplated by this invention being provided with an upstanding rib 27 arcuate in cross section, said rib terminating some distance from the opposite edges of the journal box to provide seats 28—28 adjacent the opposite edges of said top wall.

In practice, due to the fact that the pedestal members and journal box vary somewhat in size, considerable clearance is allowed between the side walls of the journal box and the guide faces of the pedestal jaws. This condition, while permitting the required vertical movement of the journal box between the jaws of the pedestal is taken advantage of in the present invention in providing means for controlling vertical movement of the box through the medium of an equalizer arrangement of a novel form.

The equalizer arrangement includes equalizer bars indicated at 29—30, and means for pivotally supporting the equalizer bars in

fixed position with reference to the truck frame. The equalizer bars 29—30 except for their opposite disposition are identical in construction. The equalizer bar 29 comprises 5 an intermediate portion 31 and inclined arms 32 and 33, the arm 32 being of somewhat greater length and thickness than the arm 33. The bar 29 is supported by means of a double wall extension 34 formed upon the jaw 15 of the 10 pedestal member 12, said bar being pivotally held in position by means of a pivot pin 35 extending through the ends of the walls of the extension 34 and through the equalizer bar at the point of juncture of the intermediate 15 portion 31 and arm 32 of the bar. The arm 32 of the bar extends through a cut-out portion in the web 22 of the jaw 15, and terminates in a bearing portion 36. The bearing portion 36 is arcuate in 20 form and the under-surface thereof is struck upon an arc having a greater radius than the arc of the rib 27, and at each side of the arcuate portion the bearing member 36 is provided with contact surfaces 37 and 38, which 25 surfaces bear upon the bearing portions 28—28 of the top wall of the journal box.

The arm 33 of the bar 29 is adapted to co-operate with a journal box 39 slidably mounted in the pedestal member 13. The pedestal member 13 is identically similar to the pedestal member 12 except for the omission of the extension 34, and the journal box is identically similar to the journal box 25, having an arcuate rib 40 corresponding in form to the arcuate rib 27 of the journal box 25. The arm 33 extends between the double walls forming the adjacent jaw of the pedestal member 13, and is provided with an arcuate terminal portion 41 off-set to one side of said bar. The under-surface of the terminal portion 41 is struck 40 upon an arc of greater radius than the arc of the rib 40 on the journal box 39, and is provided with bearing portions 42—42^a which rest upon the opposite edges of the journal box 45 outside of the rib 40, a laterally extending stop member 43 being provided for co-operation with the equalizer bar 30. The equalizer bar 30 has a short arm 44 corresponding to the arm 33 of the bar 29, and extends through the adjacent journal box guide face of the jaw of the pedestal member 13, and terminates in an offset arcuate portion 44 having its arcuate under-surface struck upon a radius similar to that of the end portion 41, and overlapping 50 said portion, and being provided with spaced contact surfaces 45—45 engageable with the opposite edges of the top wall of the journal box, the end portion 44 being provided with a laterally extending stop member 46 similar 55 to the stop member 43. The intermediate and outer end portions of the equalizer bar 30, and the opposite end of the truck not shown are 60 similar to those already described.

In operation, the load is yieldably imposed 65 on the truck frame through the suspension

means indicated at 11. Upon relative vertical movement of the journal boxes 25 and 39, due to the wheels of the truck passing over undulations in the track, the equalizer bars 29 and 30 will swing about their pivots. Assuming that the journal box 39 is moving downwardly and the journal box 25 upwardly, the equalizer bar 29 will move in a clockwise direction, and this action will result in the bearing surface 38 remaining in contact with the bearing portion 28 of the journal box, while the engaging surface 37 is lifted slightly clear of the adjacent bearing portion 28 of the journal box. The bearing portion 42^a of the arcuate portion 41 will remain in contact with the adjacent top edge of the journal box, while the contact surface 42 will be lifted slightly clear of the adjacent bearing portion of the journal box. The end portion 44 of the equalizer bar 30 will operate just the opposite to that described in connection with the portion 41 or similar to the portion 36 of the other end of the equalizer bar 29. The arcuate movement of the opposite ends of the equalizer bars 29 and 30 is 70 permitted by reason of the loose connection with the journal box in each instance, and further by reason of the clearance ordinarily left between the side walls of the journal box and the guide faces of the pedestal jaws. 75 Upon downward movement of the journal box 25 and upward movement of the journal box 39 a reversal of the action just described will take place, that is, the contact surface of the end portion 36 will remain in contact with the journal box, while the bearing portion 38 may be lifted slightly clear thereof. Of course, if the clearance between the side walls of the journal box and the guide faces of the pedestal jaws is great enough, as is usually 80 the case, the journal box may tilt somewhat, but is returned to position due to the force exerted thereon by the spaced contact surfaces of the ends of the equalizer bars and of the journal box, so that while the journal boxes might be temporarily slightly displaced, they are always returned to position 85 by movement of the equalizer bars when the truck is travelling over a flat surface.

It should be noted that the positions of the journal boxes are positively controlled by the equalizer bars, while permitting the normal vertical movements of the journal boxes in the pedestal members, the spaced points of bearing contact between the equalizer bar members and the journal boxes serving to return the journal boxes to aligned position, and maintain the same in such position thereby overcoming the tendency of the journal boxes to assume a permanently tilted condition with consequent great injury to the guide faces of the pedestal members.

While I have herein shown and described what I consider the preferred manner of carrying out the invention, the same is mere-

ly illustrative and I contemplate all changes and modifications which come within the scope of the claims appended hereto.

I claim:

5. 1. In a truck of the character described, comprising a frame; supporting means including yieldable means for carrying the load imposed upon the truck; pedestal members connected to said frame; journal boxes slidably mounted between the jaws of said pedestal members; and an equalizer member pivotally supported intermediate its ends by said frame, and having centering means upon its opposite ends directly engaging the journal boxes for opposing tilting of the same and controlling the positions thereof.
2. In a truck of the character described, the combination with a frame and pedestal members secured thereto; of journal boxes mounted for sliding movement in the jaws of said pedestals; an equalizing bar having end portions co-operating with said journal boxes, each of said end portions being provided with spaced contacting surfaces engageable with each of said journal boxes adjacent the opposite side edges of the tops thereof; and means on said frame for holding said equalizing bar against bodily movement lengthwise of said truck frame.
3. In a truck of the character described, the combination with a frame and a plurality of pedestal members, each provided with a journal box slidably disposed between the jaws thereof; a plurality of equalizer members, each of said members having one end disposed alongside of the corresponding end of the other member in overlapping relation and engageable with one of said journal boxes, and the opposite ends of both equalizer members being engageable with another journal box; and means fixed to said truck frame engaging each of said equalizer members between the ends thereof for holding the same against displacement longitudinally of said truck frame.
4. In a truck of the character described, the combination with a pedestal member having jaws; a journal box slidably mounted between the jaws of said pedestal member; and an equalizing bar pivotally mounted on an extension of said pedestal member and having one end engageable with the journal box for controlling the movement thereof, said means being in the form of spaced contacting surfaces adapted to engage the top wall of the journal box adjacent the opposite side edges thereof; and means connecting the opposite end of said equalizing member to the adjacent journal box of said truck.
5. In a truck of the character described, the combination with a frame; of pedestal members mounted on said frame, one of said pedestal members being provided with an extension; journal boxes slidably mounted between the jaws of each of said pedestal members; and an equalizer bar pivotally mounted intermediate its ends on said extension, said bar being provided with end portions providing spaced contact surfaces engageable with spaced points on the top walls of each of said journal boxes.
6. In a truck of the character described, the combination with a frame; of a plurality of pedestal members mounted on said frame; of a plurality of journal boxes, one of which is mounted between the jaws of each of said pedestal members; and a plurality of equalizer members disposed between said pedestals, each of said equalizer members being pivotally connected with said frame intermediate its ends, and each equalizer member being provided with end portions co-operating with said journal boxes, the adjacent end portions of said equalizer members being arranged in overlapping relation, and provided with spaced contacting surfaces bearing upon spaced bearing portions of the top wall of the related journal box, and the opposite ends of said equalizer members being provided with spaced contacting surfaces engageable with spaced bearing portions of the top wall of the related journal box.
7. In a truck of the character described, the combination with a frame; of a plurality of pedestal members mounted on said frame; journal boxes slidably disposed between the jaws of each of said pedestal members; an equalizer bar pivotally connected intermediate its ends upon said frame, and having end portions adapted to bear upon said journal boxes each of said end portions having an arcuate under-surface providing spaced contact points engageable with spaced bearing portions of each of said journal boxes.
8. In a truck of the character described, the combination with a frame; of a plurality of pedestal members mounted on said frame; journal boxes slidably disposed between the jaws of each of said pedestal members; an equalizer bar pivotally connected intermediate its ends upon said frame, and having end portions adapted to bear upon said journal boxes, each of said end portions having an arcuate under-surface providing spaced contact points engageable with spaced bearing portions of each of said journal boxes, the top wall of each of said journal boxes being provided with an arcuate rib struck upon a radius of less extent than the radius of the arc defining the spaced contacting points of each end portion of said equalizer member.
9. In witness that I claim the foregoing I have hereunto subscribed my name this 17th day of May, 1927.

JOHN F. O'CONNOR.
